WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

MANUAL TELEPHONE SYSTEM.

Application filed July 28, 1924. Serial No. 728,565.

This invention relates to telephone systems and more particularly to telephone systems having one or more offices. In such telephone systems it has been customary to provide so-called order wires interconnecting the various offices through which an operator at an originating office transmits the wanted number to a B operator at a distant office and over which this last named operator in turn assigns a trunk for the use of the A operator in extending a call. Such order wire operation has proved to be especially inefficient during busy periods and has resulted in numerous wrong connections.

It is the purpose of the present invention to provide an improved arrangement whereby separate order wires may be dispensed with to the end that the operation of a multi-office system may be greatly facilitated and the number of incorrect connections reduced to a minimum.

One of the features of the present invention resides in the provision of means whereby an operator at the originating office may automatically select an idle trunk to an operator's position at a distant office and whereby the designation of the trunk so selected is indicated to the operator at the originating office.

Another feature of the invention consists of the arrangement whereby an operator's telephone set is automatically connected to a cord circuit and then subsequently automatically disconnected from the cord circuit and connected to an idle trunk leading to an operator's position at a distant wanted office.

A further feature of the invention includes the arrangement whereby a trunk extending between two offices, may take the place of an order wire.

The drawings with Figs. 1, 2 and 3 arranged in the order named, diagrammatically represent a portion of a telephone system including the present invention. Fig. 1 represents a telephone line and an A operator's cord circuit of an originating exchange or office. Fig. 2 represents a portion of a trunk circuit leading to a distant office and also shows several groups of relays by which such an idle trunk leading to a wanted office is selected. Fig. 3 represents the remainder of said trunk which terminates in a manual connecting plug at a B operator's position in the wanted office. At the extreme right

of Fig. 3 there is indicated a telephone line which is referred to as a called telephone line.

For purposes of this description it is assumed that one hundred trunks extend between office Number 1 and office Number 2, but in practice this number is dependent on the traffic. Although the showing of the trunk selecting arrangement is very much abbreviated, it will be understood that at each operator's position there are provided ten of the multi-contact relays similar to relay 52 and that ten other relays similar to relay 55, are also provided at each position. It will also be noted that each trunk is multipled to contacts of a multi-contact relay at each operator's position. This will appear by tracing the multiple connections from the conductors 62 and 66. A similar group of trunks leading to each office is accessible to each operator's position and a single office key similar to 50 appearing in the lower left hand corner of Fig. 2 is provided at each operator's position for each of the various offices accessible to that position.

It is believed that the invention will best be understood by describing the method of extending a telephone connection from a subscriber's substation indicated at A, to a subscriber's substation whose telephone line terminates at a distant office.

When the subscriber at A removes his receiver from its switch-hook, the line relay 5 is energized in the well known manner over the two sides of the calling line in series and thereby lights the line lamp 6. The operator whose cord circuit is shown in Fig. 1 then inserts the answering plug 7 of this cord circuit into the jack 8 of the calling line. This operation is effective to energize the cut-off relay 9 and the operator's bar relay 10 in a circuit extending from grounded battery, through the right hand high resistance winding of relay 10, through the sleeve contacts of the plug 7 and jack 8, and winding of the cut-off relay 9 to ground. As soon as the cut-off relay 9 is actuated it opens the energizing circuit of the line relay 5, which relay deenergizes and opens the circuit of the lamp 6 to extinguish it. The operator's bar relay 10 when operated, closes a locking circuit for itself through its low resistance left hand winding and through its left hand armature and front contact

over the remainder of the circuit previously described. As is well known, the high resistance and low resistance windings of the relay 10 are provided to prevent a second operator's telephone set from being connected to a calling subscriber's line at the same time, in the event that two operator's should simultaneously connect the answering ends of their cord circuits to the same calling line.

When the relay 10 is operated it closes a circuit from ground, its outer right hand armature and front contact, uppermost armature and back contact of relay 11, winding of the slow releasing relay 12, winding of the relay 13, left hand winding of the relay 14, winding of the high resistance relay 15, to grounded battery. The resistance of the relay 15 is such (5000 ohms for example) that it is operated in this circuit, but the other mentioned relays in series therewith, are not operated at this time. With the relay 15 operated, an energizing circuit is closed from grounded battery, right hand winding of the relay 14, front contact and armature of relay 15, to ground. When the relay 14 is thus energized, it extends a circuit from grounded battery, its front contact, armature and left hand winding, and thence through the windings of relays 13 and 12, over the remainder of the circuit previously described as extending to ground at the right hand front contact and armature of relay 10. Relays 12 and 13 are energized in this last circuit. Relay 13 closes a break-point in the operating circuit of the meter 16 and with the relay 12 energized the operator's cut-in relay 18 is energized from grounded battery winding of relay 18, front contacts and armatures of relay 12, conductor 19, and the winding of relay 17, to ground. The relay 18 is thereby energized and at its left hand armatures and front contacts, extends the operator's telephone set through the conductors 59, 69, 45 20 and 21 over the answering end of the cord circuit in use, to the calling subscriber's line. The relay 17 is energized in series with the relay 18 and closes the remaining break-point in the circuit of the meter 16, causing 50 the same to operate. The operation of relay 17 short circuits and releases relay 13, which opens the circuit of the meter allowing it to release after making a record that the operator has answered one call.

The relays 13, 14, 15, 17 and the impedance coil 22, are common to an operator's position and are provided to permit the operator to start a second call through a second cord circuit while she is completing the connection on a first cord circuit such as that shown in Fig. 1. This arrangement permits the operator to "plug up" a second call while she is pressing the ringing key to apply ringing current over a first cord circuit. The arrangement of relays is such

that only two calls may be in the process of completion by one operator at the same time. If the operator "plugs up" more than two calls before any one connection is completed, then all of these calls will fail.

From the preceding description it will be seen that the operator's telephone set is connected to the cord circuit by the operation of relay 18 and that this relay is controlled by relay 12. When one call is answered, relay 12 will operate as above described and will be released when relay 11 is energized, after the completion of the connection, as will be later described. After the completion of a first connection, a second answering cord similar to 7 is inserted in an answering jack. The relay 10 at the second cord operates, but relay 12 at this second cord cannot operate, because of the shunt path to ground through coil 22, which has been placed in the common operating circuit of relay 12 by the operation of relay 17. This shunt path does not prevent relay 12 from holding when once operated, but it does prevent it from operating. When the resistances of relays 12, 13, 14, 15 and coil 22 are properly chosen, the above operation is obtained without the use of marginal relays or special adjustments. When the first connection is completed, the circuit of relay 12 associated with this connection is opened and it deenergizes. Relay 12 of the second connection now immediately operates, because the above described shunt path is removed, when relay 17 releases at the completion of the first connection. These resistance values are such, however, that if more than one call is "plugged up" while another is in the process of completion, the additional shunt path to ground through the additional relay 12 will prevent the operation of either.

As soon as the operator's telephone set, which is indicated at the lower part of Fig. 2, is connected to the calling telephone line through the answering end of the cord circuit, the operator inquires for the number of the wanted telephone line. On ascertaining that the wanted line terminates at a distant office the operator depresses the single office key 50, which is individual to the wanted office. The operation of key 50 closes a circuit from grounded battery over conductor 51, winding of the multi-contact relay 52, its continuity spring and back contact, innermost back contact and armature of relay 53, to ground. Relay 52 is thus energized and closes a locking circuit for itself from grounded battery, at key 50, winding of relay 52 its continuity spring and innermost armature, winding of relay 54, to ground. The closure of this circuit energizes relay 54 which at its left hand armatures and front contacts closes break-points in the operator's telephone circuit. With the group relay 52

energized, relay 55 is actuated from grounded battery, winding of this relay, its continuity spring and back contact, conductor 56, innermost left hand front contact and armature 5 of relay 52, conductor 57, uppermost back contact and armature of relay 58, to ground. With relays 52 and 55 actuated the operator's telephone set is connected to the selected idle trunk over conductor 59, outer armature and 10 front contact of relay 54, armature and contact 60 of relay 55, contact 61 and armature of relay 52, conductor 62 to conductor 63 of the selected trunk, thence through the lower side of the repeating coil of Fig. 3, through 15 both windings in series of relay 64, upper left hand winding of the repeating coil, trunk conductor 65, conductor 66, armature and contact 67 of relay 52, front contact and armature 68 of relay 55, innermost front 20 contact and armature of relay 54, conductor 69 to the other side of the operator's telephone set. The impedance coil 95 is bridged to this circuit so that the relay 64 is energized in this circuit to effect the operation 25 of the slow releasing relay 70 from grounded battery, winding of this relay, front contact and armature of relay 64, to ground. This causes the supervisory lamp 71 to be lighted in a circuit from grounded battery, the lamp 30 71, armatures and back contacts of relays 75 and 72, innermost front contact and armature of relay 70, outer back contact and armature of relay 73, to ground.

At this time a tone is transmitted to the 35 A operator's set from the source of tone current, outermost back contact and armature of relay 72, armature and back contact 74 of relay 75, left hand front contact and armature of relay 70, right hand winding of relay 73 and thence through the condenser and left hand winding of relay 73, to grounded 40 battery. A tone current is then induced through the trunk including the conductors 63 and 65 and thence to the A operator's 45 telephone set. This tone is heard in the A operator's receiver until the trunk, whose conductors are designated 63 and 65, is inductively connected to the B operator's telephone set, over conductors 76. Only one 50 trunk at a B operator's position can be connected to the operator's circuit at one time and when this takes place the tone is disconnected from the A operator's telephone. The disconnection of the tone is an indication 55 to the A operator to repeat the wanted number without being challenged by the B operator.

As soon as the relay 75 is operated as will 60 later be described, the supervisory lamp 71 is intermittently lighted in a circuit from grounded battery, lamp 71, right hand armature and front contact of relay 75 and the flashing interrupter to ground. Under the control of this circuit the supervisory lamp 65 71 flashes and when the B operator receives

the wanted number, she announces the number of the flashing lamp, which assigns to the A operator the trunk to be used in completing the connection.

It will thus be seen that it is not necessary 70 for the B operator to choose a trunk out of a particular group leading to the originating office. The trunk is automatically selected and the flashing of its supervisory lamp is an indication as to which trunk has been selected. It may be well to mention at this point that the wiring of the B operator's cut-in circuit for three trunks is shown in Fig. 3, together with the common circuit arrangement for preventing more than one 75 trunk from being connected to the B operator's circuit at one time. It will be understood that all of the trunks at this position are wired in the same way as those shown in this figure. When a trunk is chosen at the 80 originating end its relay 70 is energized and if no other trunk at the B position is connected to the operator's telephone circuit, the relay 75 is operated from grounded battery, release key 78, back contact and armature of relay 79, right hand winding of relay 75, outer armature and back contact of relay 72, continuity spring and armature of relay 70, ground. Relay 75 when operated closes a locking circuit for itself from grounded 85 battery, release key 78, winding of relay 79, left hand winding, front contact and armature of relay 75, armature and front contact of relay 70, back contact and armature of relay 72, to ground. Relay 79 upon operation opens all the energizing circuits to all of the relays corresponding to 75 at this position, so that the operation of a relay corresponding to 70 of another trunk circuit cannot result in the connection of a second trunk 90 to this B operator's telephone set.

From the foregoing description it will be understood that the supervisory lamp 71 is lighted steadily, as soon as the trunk is automatically selected, but is caused to flash 100 intermittently as soon as the operator's telephone set is connected to this selected trunk. The series circuit extending from ground through the continuity spring 80 insures that only one trunk can be connected to the operator's telephone circuit when a call is plugged up, even though several are waiting an operator's attention. The lock-out circuit controlled by the relay 79 insures that a call on a trunk near the ground end of the series will not cut-in and release one trunk which is connected to the operator's telephone circuit and which is also located farther from the ground end of the series.

When the A operator receives the assignment of the trunk that has been selected, she inserts the calling plug 23 into the jack 77 of this trunk and then depresses some one of the ringing keys such as 26. The connection of the calling end of the cord circuit 125 130

to the selected trunk results in the operation of the slow releasing relay 29 in a circuit extending from grounded battery, winding of this relay, back contact and continuity 5 spring of relay 11, sleeve contacts of the plug 23 and the jack 77, resistance, to ground. The depression of the ringing key 26 effects the operation of relay 28 and the actuation of this relay completes a circuit from 10 ground, right hand armature and front contact of relay 28, inner armature and front contact of relay 29, upper winding of relay 11, to grounded battery. This results in the energization of relay 11, whereby this relay 15 is locked operated from grounded battery, through its lower winding, lowermost armature and continuity spring to ground through the sleeve contacts of the plug 23 and the jack 77. The operation of the relay 20 11 also closes a break-point in the calling end of the cord circuit. The operation of relay 28 also closes a circuit from ground, left hand front contact and armature, outer armature and front contact of relay 29, winding 25 of relay 30, to ground. The ringing relay 32 is also energized at this time in a circuit from grounded battery, resistance, winding of this relay, right hand armature and back contact of relay 34, inner front 30 contact of relay 29 and thence to ground at the armature and front contact of relay 28. Although ringing current is selected at the A position, in order to render the operation the same as in the case of a local call, the 35 ringing current is immediately tripped as will hereinafter be described.

As soon as the calling plug 23 is placed in the jack 77 of the assigned trunk, a circuit is closed from ground at the lower armature 40 and back contact of relay 81, winding of the slow releasing relay 82 through the ring contacts of the jack 77 and plug 23, inner most armature and front contact of the ringing relay 32, winding of the trip relay 38, 45 right hand armature and back contact of relay 30, inner armature and back contact of relay 37 and thence to the source of ringing current. This circuit is effective to energize the trip relay 38 which relay at its 50 armature and front contact places a short circuit about the ringing relay 32. This last named relay is thereupon deenergized to render the conductors of the cord circuit continuous. It will thus be seen that as soon 55 as the plug 23 is connected to an outgoing trunk, ringing current is disconnected from the cord circuit.

Relay 82 on operating closes a circuit for relay 81 through the upper winding of this 60 last named relay, armature and front contact of relay 82, armature and back contact of relay 32, left hand winding of relay 31, to grounded battery. Relay 81 when operated opens the circuit of relay 82 and closes 65 a locking circuit for itself through its lower

winding, inner front contact and armature, sleeve contacts of the jack 77 and plug 23, continuity spring, armature and lower winding of relay 11, to grounded battery. Relay 81 at its lowermost armature and front contact closes an operating circuit for the relay 58, which relay maintains this trunk unselectable as long as the plug 23 is in the jack 77. 70

The B operator after receiving the designation of the wanted telephone line inserts the calling plug 83 into a multiple jack 84 of this wanted line and depresses a ringing key such as 85. This operates the relay 86, which in turn closes an operating circuit 80 for the relay 87 from grounded battery, its left hand winding, inner armature and front contact of relay 88, outer front contact and armature of relay 86, to ground. Also when relay 86 is operated it effects the energization of the relay 72 in a circuit traceable 85 from grounded battery, left hand winding of relay 72, inner left hand front contact and armature of relay 88, inner front contact and armature of relay 86, to ground through 90 the winding of relay 91. The energization of relay 72 at its armature 94 opens the locking circuit for the relay 75, so that the B operator's telephone set becomes accessible 95 to any of the other trunks. Relay 87 on operation closes a locking circuit for itself through its left hand winding, left hand front contact and armature, conductor 89, inner armature and back contact of relay 73, outer front contact and armature of relay 72, to ground. At this time the ringing 100 relay 90 is also operated from grounded battery, resistance, winding of the relay 90, inner front contact and armature of relay 88, inner front contact and armature of relay 86, winding of the relay 91, to ground. Ringing current is supplied to the called line from the 16 cycle source of current, innermost front contact and armature of relay 87, back contact and armature of relay 92, 105 outer front contact and armature of relay 70, winding of the trip relay 93, inner front contact and armature of relay 90, ring contacts of the plug 83 and jack 84 through 110 the wanted substation circuit on the party line, tip contacts of the jack 84 and plug 83, and thence to ground. Under the control of this circuit ringing current is supplied 115 to the ringer at the wanted substation until the wanted party answers, at 120 which time the trip relay 93 is energized to short circuit the ringing relay 90, and disconnect ringing current. When the called party answers the supervisory relay 73 operates and at its left hand armature and front contact places a shunt circuit about 125 the high resistance winding of relay 64. This operation is effective to cause the energization of the supervisory relay 31, shown near the right of Fig. 1. 130

At the close of the conversation, when the subscriber at B replaces his receiver on its switchhook, the supervisory relay 73 de-energizes and opens the short circuit about 5 the high resistance winding of relay 64. The inclusion of this high resistance winding in series with the trunk conductors 63 and 65, results in the deenergization of the supervisory relay 31 at the A operator's position, shown in Fig. 1. The deenergization of 10 the supervisory relay 31, of Fig. 1 closes a circuit for lighting the supervisory lamp 46, which circuit is completed from grounded battery, lamp 46, back contact and middle 15 armature of relay 32, outer back contact and armature of relay 31, inner armature and front contact of relay 11, to ground. The disconnect lamp 71 of the B operator's position is also lighted in a circuit closed from 20 grounded battery, lamp 71, armature and back contact of relay 75, armature and back contact of relay 72, innermost right hand front contact and armature of relay 70, back contact and armature of relay 73, to ground. 25 The lighting of the lamp 71 at this time is a signal to the B operator to remove the plug 83 from the jack 84 of the called line. Also when the calling party replaces his receiver on its switchhook, the supervisory relay 39 30 deenergizes to light the answering supervisory lamp 41 in a circuit from grounded battery, lamp 41, inner armature and back contact of relay 39, inner armature and front contact of relay 10, winding of the impedance coil 45, to ground. The lighting of 35 lamps 41 and 46 is a signal to the A operator to disconnect plugs 7 and 23.

For the purpose of allotting an idle trunk for use, a relay such as 58 is energized as 40 soon as a trunk is seized. It has been assumed that one hundred trunks are provided between the offices Number 1 and Number 2. These one hundred trunks are divided into ten groups of ten each and a group relay 45 such as 53 is provided individual to each group. When all of the trunks of a group are in use the relays such as 58^A and 58^B associated therewith are held energized, so that the group relay 53 is actuated to assign another group of trunks for use. Under such 50 conditions when an operator depresses an office key, the multi-contact relay such as 52^A is operated, so that an idle trunk from another group is selected.

55 It will thus be seen that novel means are provided for connecting the operator's telephone set through several different portions of a telephone connection and for obviating the use of a separate order wire between operators' positions.

What I claim is:

1. In a telephone system, an A operator's position, a B operator's position, telephone lines terminating at each of said positions, 60 a trunk extending between said positions, 65 means for selecting said trunk for use, a cord circuit at said A operator's position for interconnecting any of the telephone lines terminating thereat, with said trunk, an operator's telephone set at said A operator's 70 position, means responsive to the connection of said cord circuit to a calling telephone line for connecting said operator's telephone set thereto, means operating responsive to the selection of said trunk for disconnecting 75 said telephone set from said telephone line and for connecting it to said trunk, and means for connecting said trunk to a wanted telephone line terminating at said B operator's position. 80

2. In a telephone system, an A operator's position, a B operator's position, telephone lines terminating at each of said positions, a plurality of trunks serving to interconnect said A and B operators' positions, an operator's telephone set at each of said A and B operators' positions, means for selecting a trunk for use, a cord circuit for interconnecting a calling telephone line at the A operator's position with any of said trunks, 90 means responsive to the connection of said cord circuit to a calling telephone line for connecting said A operator's telephone set thereto, means responsive to the selection of an idle one of said trunks for connecting 95 said B operator's telephone set thereto and for disconnecting said A operator's set from the calling telephone line and for connecting it to the selected trunk whereby said A and B operators may converse thereover, means 100 for connecting the calling telephone line to the selected trunk through said cord circuit, and other means for connecting the selected trunk to a wanted telephone line. 105

3. In a telephone system an A operator's position, a B operator's position, telephone lines terminating at each of said positions, trunk lines extending between said positions, an operator's telephone set at said A operator's position, an operator's telephone set at said B operator's position, a cord circuit connectible to a calling telephone line, means operating on connection of said calling telephone line to said cord circuit for extending said A operator's telephone set thereto, means including a plurality of relays for selecting an idle one of said trunks, means including an office key at said A operator's position for controlling said relays, means responsive to such selection for indicating 110 at said B operator's position the designation of the selected trunk, means responsive to said selection for disconnecting said A operator's telephone set from said calling telephone line and for interconnecting said A 115 operator's telephone set and said B operator's telephone set over the selected trunk whereby the B operator may report the designation of the selected trunk to the A operator, means for connecting said cord circuit 120 to 125

cuit to the selected trunk, and means for connecting the selected trunk to the wanted telephone line.

4. In a telephone system, an A operator's position, a B operator's position, telephone lines terminating at said A operator's position, party telephone lines terminating at said B operator's position, an operator's telephone set at each of said positions, a plurality of trunks for interconnecting said positions, a plurality of sources of signaling current at said B operator's position for selectively signaling stations on the party lines terminating thereat, a single ringing key common to said plurality of trunks for each source of ringing current, a cord circuit at said A operator's position, manual means for extending said cord circuit to a telephone line on the initiation of a call thereover, means responsive to said extension for connecting said A operator's telephone set to said cord circuit, means controlled from said A operator's position for automatically selecting an idle trunk terminating at a B operator's position, means operating responsive to said selection for disconnecting said operator's telephone set from said A cord circuit and for connecting it to said selected trunk, other means responsive to the selection of said trunk for connecting said B operator's telephone set to said selected trunk whereby said A operator's telephone set and said B operator's telephone set are telephonically connected together over said trunk, means for connecting the cord circuit to the selected trunk, means for connecting said trunk to the wanted telephone line, means responsive to the connection of said trunk to the wanted telephone line for placing said single ringing key in operative relation to the selected trunk to the exclusion of the other trunks, means controlled by said common key for selectively applying ringing current to the wanted telephone line, means controlled over said wanted telephone line for disconnecting the signaling current, and means controlled from said wanted telephone line over the selected trunk for operating said supervisory signal.
5. In a telephone system, an A operator's position, a B operator's position, telephone lines terminating at each of said positions, certain of said telephone lines being party lines, an operator's telephone set at each of said positions, a plurality of trunks for interconnecting said positions, a plurality of sources of signaling current at said B operator's position for selectively signaling stations on the party lines terminating thereat, a single ringing key common to said plurality of trunks for each source of ringing current, a cord circuit at said A operator's position provided with a supervisory signal, manual means for extending said cord circuit to a telephone line on the initiation of a call thereover, means responsive to said extension for connecting said telephone set to said cord circuit, means con-

trolled from said A operator's position for automatically selecting an idle trunk terminating at a B operator's position, means operating responsive to said selection for disconnecting said operator's telephone set from said A cord circuit and for connecting it to said selected trunk, other means responsive to the selection of said trunk for connecting said B operator's telephone set to said selected trunk whereby said A operator's telephone set and said B operator's telephone set are telephonically connected together over said trunk, means for connecting the cord circuit to the selected trunk, means for connecting said trunk to the wanted telephone line, means responsive to the connection of said trunk to the wanted telephone line for placing said single ringing key in operative relation to the selected trunk to the exclusion of the other trunks, means controlled by said common key for selectively applying ringing current to the wanted telephone line, means controlled over said wanted telephone line for disconnecting the signaling current, and means controlled from said wanted telephone line over the selected trunk for operating said supervisory signal.

6. In a telephone exchange system, a calling line, a plurality of cord circuits each being provided with an answering and a calling plug, an operator's telephone set, means responsive to the connection of one of said answering plugs to said line for connecting said operator's telephone set to one of said cord circuits, a group of trunk circuits, a key common to said cord circuits and to said trunk circuits, and means responsive to the actuation of said key for disconnecting said operator's telephone set from said cord circuit and for connecting said operator's telephone set to one of said trunk circuits.

7. In a telephone exchange system, a calling line, a plurality of cord circuits each being provided with an answering and a calling plug, an operator's telephone set, means responsive to the connection of one of said answering plugs to said line for connecting said operator's telephone set to one of said cord circuits, a group of trunk circuits, a key common to said cord circuits and to said trunk circuits, means responsive to the actuation of said key for disconnecting said operator's telephone set from said cord circuit and for connecting said operator's telephone set to one of said trunk circuits, and means for thereafter connecting said cord circuit to said trunk circuit.

8. In a telephone system, an A operator's position, a B operator's position, telephone lines terminating at each of said positions, a plurality of trunks, serving to interconnect said A and B operators' positions, an operator's telephone set at each of said A

and B operators' positions, means including automatic switching devices for selecting a trunk for use and for connecting said A operator's telephone set thereto, a cord circuit for interconnecting a calling telephone line at the A operator's position with the selected one of said trunks, means responsive to the connection of said cord circuit to a calling telephone line for connecting said A operator's telephone set thereto, means responsive to the connection of said cord circuit to the selected one of said trunks for connecting said B operator's telephone set thereto, and means responsive to the connection of said trunk to one of said telephone lines at said B operator's position for disconnecting said B operator's set from said trunk.

9. In a telephone system, an A operator's position, a B operator's position, telephone lines terminating at each of said positions, a plurality of trunks serving to interconnect said A and B operator's positions, an operator's telephone set at each of said A and B operator's positions, means for selecting a trunk for use, a cord circuit for interconnecting the calling telephone line at the A operator's position with any of said trunks, means responsive to the connection of said cord circuit to a calling telephone line for connecting said A operator's telephone set thereto, means responsive to the selection of an idle one of said trunks for disconnecting said A operator's telephone set from the calling telephone line, means responsive to the connection of said cord circuit to the selected one of said trunks for connecting said B operator's telephone set thereto, and means responsive to the connection of said trunk to one of said telephone lines at said B operator's position for disconnecting said B operator's telephone set from said trunk.

10. In a telephone system, an A operator's position, a B operator's position, telephone lines terminating at each of said positions, a plurality of trunks serving to interconnect said A and B operator's positions, an operator's telephone set at each of said A and B operators' positions, means for selecting a trunk for use, a cord circuit for interconnecting a calling telephone line at the A operator's position with the selected one of said trunks, means responsive to the connection of said cord circuit to a calling telephone line for connecting said A operator's telephone set thereto, means responsive to

the connection of said cord circuit to the selected one of said trunks for connecting said B operator's telephone set thereto, a key common to said B operator's position, and means responsive to the operation of said key for disconnecting said B operator's telephone set from said trunk.

11. In a telephone system an A operator's position, a B operator's position, telephone lines terminating at each of said positions, an operator's telephone set at each position, a plurality of trunks for interconnecting said positions, a cord circuit at said A operator's position provided with manual switches for connecting said cord circuit to a calling telephone line and to any selected trunk, automatic means responsive to the connection of said cord circuit to a calling telephone line for extending said A operator's telephone set thereto, a key common to said trunks, a set of relays for each trunk, means including an allotter and said key for variably operating said sets of relays to select an idle trunk and to connect said A operator's telephone set to said selected trunk, means for connecting said B operator's set to said selected trunk, and means for connecting the selected trunk to a wanted telephone line.

12. In a telephone system an A operator's position, a B operator's position, telephone lines terminating at each of said positions, an operator's telephone set at each position, a plurality of trunks for interconnecting said positions, a cord circuit at said A operator's position provided with manual switches for connecting said cord circuit to a calling telephone line and to any selected trunk, automatic means responsive to the connection of said cord circuit to a calling telephone line for extending said A operator's telephone set thereto, a key common to said trunks, a plurality of group-selecting and unit-selecting relays common to said trunks, means including an extended starter wire circuit and said key for operating certain of said relays to select an idle trunk and to connect said A operator's telephone set to said selected trunk, means for connecting said B operator's telephone set to said selected trunk, and means for connecting the selected trunk to a wanted telephone line.

In witness whereof, I hereunto subscribe my name this 25th day of July, A. D. 1924.

WINFRED T. POWELL.
